UNITED STATES PATENT OFFICE.

CAMILLE MERCADER, OF BRADDOCK, AND CLARENCE L. WILMOT, OF PITTSBURG, PENNSYLVANIA.

SKELP-HANDLING APPARATUS.

SPECIFICATION forming part of Letters Patent No. 678,794, dated July 16, 1901.

Application filed October 6, 1900. Serial No. 32,231. (No model.)

To all whom it may concern:

Be it known that we, CAMILLE MERCADER, of Braddock, and CLARENCE L. WILMOT, of Pittsburgh, in the county of Allegheny and 5 State of Pennsylvania, have invented a new and useful Improvement in Skelp - Handling Apparatus, of which the following is a full, clear, and exact description, reference being had to the accompanying drawings, forming 10 part of this specification, in which—

Figure 1 is a plan view showing the preferred form of our apparatus. Fig. 2 is a sectional end elevation of the transfer apparatus, and Fig. 3 is a cross-section of the heating-furnace and transfer apparatus.

Our invention relates to the handling of skelp as it is taken from the reheating-furnace and more particularly to the drawing of the heated skelp from the furnace and passing 15 it to the scarfing-rolls.

Heretofore in drawing the skelp from the furnace and inserting it in the scarfing-rolls difficulty has been experienced in bringing the several strips of skelp into the proper position to pass through the scarfing-rolls, and 20 it has been proposed to move the scarfing-rolls themselves to different points of the furnace-mouth in order to bring them to the proper point for the insertion of the different 25 pieces of skelp as they lie in the furnace; but this method involves the changing of position of the whole scarfing apparatus and 30 is expensive and disadvantageous.

Our invention is designed to overcome the 35 above difficulties; and it consists in providing apparatus for withdrawing the skelp from the furnace and then transferring it sidewise to the proper point in line with the pass of the scarfing-rolls.

It further consists in providing a stop by 40 which the skelp, which is preferably moved sidewise in parallel lines by endless carriers, is stopped in the proper place to enter the scarfing-rolls, and, further, in the construction and arrangement of the parts as herein- 45 after more fully described, and set forth in the claims.

In the drawings, 2 represents a reheating-furnace for the skelp having a wide exit- 50 opening 3. In front of this opening we place a pair of feed-rolls 4, the upper of which is

preferably yieldingly pressed against the lower by counterweights 5, connected to the upper-roll bearings. The lower roll is shown as positively driven by wabbler connections 55 6, with a set of driving-pinions 7, which also drive the scarfing-rolls 8. The driving-pinions are thus placed between the feed-out rolls and the scarfing-rolls in parallelism therewith and actuate both sets. 60

In front of both sets of rolls extends a table or hot bed 9, having longitudinal rails 10, which are vertically movable in parallel lines. These rails or supports are preferably carried on I-beam 11, to which are pivoted links 65 12 and 13, secured to shafts 14 and 15, respectively. The shaft 14 is provided with a rock-arm 16, having a pivotal link connection 17 with the plunger 18 of a small motive cylinder 19. The supporting-rails may thus be 70 raised and lowered in parallel lines.

Between the longitudinal rails and in line with the mouth of the furnace are a series of open supports 20, preferably having a series of parallel strips set edgewise and extending at right angles to the vertically-movable 75 rails.

A portion of the rails 10 are grooved or otherwise formed to receive the longitudinal flexible wire ropes 21, which extend over 80 end pulleys 22 and 23, the pulleys 23 being mounted on a shaft 24, having bevel-gear connections 25 with a short shaft 26, driven by gear connections 27 from the scarfing-rolls.

A series of feed-rollers 28 lead to the scarfing-rolls and are placed between the end portions of the longitudinal table - rails, these 85 rolls having bevel-gear connections 29 with a shaft 30, driven by a sprocket connection 31 from the shaft 24. To stop the skelp or 90 plate in proper position on the feed-rollers, we provide the wide plate 32, which is secured rigidly between the feed-rollers and preferably forms the side plate of a skeleton support 33, similar to those at the other end of 95 the table.

In the operation of the device the operator working from the charging end of the furnace pushes any one of the pieces of skelp lying in the furnace into engagement with that portion of the feed-rolls in front of such piece. The feed-rolls thereupon move the piece out- 100

ward over the skeleton supports 20, upon which it then rests. The motor 19 then being actuated, the longitudinal rails 10 are moved up and lift the skelp from the tables, 5 and the ropes then move it laterally along them in parallel lines until it is brought in engagement with the stop 32. The rails are then lowered and the piece is immediately carried forward into the scarfing-rolls by the 10 feed-rollers which are driven therefrom. In the meantime the operator pushes another strip into the feed-out rolls of the furnace. The operation thus goes on rapidly and continuously.

15 The advantages of our invention result from the bringing of each piece of skelp into correct position to enter the scarfing-rolls without the use of skilled labor and with great rapidity. The location of the scarfing-rolls 20 is peculiarly advantageous, as the feed-out rolls and the scarfing-rolls may thus be driven from the same connections, while the skelp is easily brought into position to enter the scarfing-rolls. The skelp is automatically 25 stopped in the right position to enter the rolls, and the whole operation may be carried out rapidly and at small expense.

Many variations may be made in the form 30 and arrangement of the table and the rolls, and means other than the feeding-rolls may 35 be employed to feed the strip from the furnace on the table without departing from the scope of our invention.

We claim—

35 1. A skelp-heating furnace having an outlet-opening, scarfing-rolls at one side of the outlet, and a table extending transversely in front of the outlet and the scarfing-rolls, and having mechanism for carrying the skelp 40 sidewise thereon; substantially as described.

2. A heating-furnace having an outlet-opening, feed-out rolls near the opening, supports

in front of the feed-out rolls, a pair of scarfing-rolls at one side of the furnace-opening, and carriers arranged to move the skelp sidewise to a position in front of the scarfing-rolls; substantially as described. 45

3. The combination with scarfing-rolls, of a feed-table extending thereto, a furnace at one side of the scarfing-rolls, a table extending transversely in front of the scarfing-rolls and furnace, and a vertically-movable carrier arranged to move the metal sidewise and take it to the feed-table; substantially as described. 50

4. A table having plate-supports at one end, vertically-movable carriers between the supports and extending longitudinally of the table, a feed-table at the other end of the supporting table or bed, and stops arranged to 60 stop the metal in proper position on the feed-table; substantially as described.

5. A heating-furnace having an outlet-opening, scarfing-rolls at one side of the opening, a table extending in front of the outlet and 65 scarfing-rolls, and having longitudinal rails or supports, and vertically-movable carriers arranged to slide the skelp sidewise along the supports; substantially as described. 55

6. A heating-furnace having an outlet-opening, rolls at one side thereof, a table extending transversely in front of the furnace-opening and rolls, mechanism for carrying the metal sidewise along said table, and mechanism for stopping metal at the proper place in 70 front of the rolls; substantially as described. 75

In testimony whereof we have hereunto set our hands.

CAMILLE MERCADER.
CLARENCE L. WILMOT.
